(57) **CLAIM**

The ornamental design for a light pendant, as shown and described.

DESCRIPTION

FIG. 1 is a top view of our new design when used as a ceiling light pendant;

FIG. 2 is a front view thereof;

FIG. 3 is a side view thereof;

FIG. 4 is a top view of our new design when used as a wall lamp;

FIG. 5 is a side view thereof;

FIG. 6 is a front view thereof;

FIG. 7 is a top view of our new design when used as a floor lamp;

FIG. 8 is a front view thereof; and,

FIG. 9 is a side view thereof.

The broken lines represent portions of the light pendant that form no part of the claimed design.
